IRONING PRESS

Stephen Evans Alley, Christopher Stanley Gardner, and Stephen Eric Alley, Shrewsbury, England

Application June 24, 1941, Serial No. 399,571
In Great Britain March 28, 1940

6 Claims. (Cl. 38—40)

This invention is for improvements in or relating to ironing presses and is concerned with presses of the type comprising a movable pressing head which is brought into and out of operative position in which it presses articles placed between it and a co-operating buck. The invention has for one of its objects to eliminate the use of springs which have heretofore been used to bring the movable head out of operative position. Other objects of the invention are to reduce or eliminate jar or shock in the operation of the press and to provide a generally more efficient construction than has heretofore been available.

According to the primary feature of the present invention, there is provided an ironing press of the type described, in which fluid pressure is employed to bring the movable head into operative position and apply the ironing pressure and is also employed to bring the movable head out of operative position. Thus it will be seen that there is no need to employ return springs for bringing the buck out of operative position.

According to the invention the fluid pressure operates in both directions through a piston and cylinder and it is a feature of the invention to provide a construction comprising a piston head, a trunk reaching from one face thereof, a two-diameter cylinder, the larger and smaller parts of which closely fit the piston head and the piston trunk respectively, and the diameter of the trunk being such that the opposed exposed faces of the piston head in the larger part of the piston head in the larger part of the cylinder are of different areas, and means for admitting fluid pressure to both ends of the larger part of the cylinder. It will be appreciated that in this construction the piston face of smaller area takes the form of an annulus and it is preferred to employ this piston face to bring the movable head out of operative position. The pressure in the annular space formed by the piston head and trunk is also employed according to the invention to cushion the movement of the piston in the direction in which it moves to apply pressure to the articles between the bucks. For the same or a similar purpose the rate of exhaust of pressure fluid from the said annular space may be regulated.

It is a further feature of the invention to employ the cylinder, in which the piston operates, to stiffen or brace the frame of the press.

For a more complete understanding of these and other features of the invention there will now be described, by way of example only and

5 with reference to the accompanying drawings, one constructional form of ironing press according to the invention. It is to be understood, however, that the invention is not restricted to the precise constructional details set forth.

In these drawings:

Figure 1 is a side elevation of an ironing press with certain of the parts of the frame removed and with the movable head in inoperative position;

Figure 2 is a sectional elevation on the line 2—2 of Figure 4, showing the movable head in operative position;

Figure 3 is a detail elevation looking in the direction of the arrow 3 in Figure 2;

Figure 4 is a front elevation of the press with the parts in the position shown in Figure 2;

Figure 5 is a detail sectional view on the line 5—5 of Figure 2 on a scale larger than that of Figure 2;

Figure 6 is a detail sectional view on the line 6—6 of Figure 5 on a scale larger than that of Figure 5;

Figure 7 is a detail sectional view on the line 7—7 of Figure 6;

Figure 8 is a detail sectional view on the line 8—8 of Figure 1 on a scale larger than that of Figure 1;

Figure 9 is a plan view of the parts shown in Figure 8 with the upper part of the finger guard removed;

Figure 10 is a front elevation of the parts shown in Figures 8 and 9, and

Figure 11 is a section on the line 11—11 of Figure 9.

Like reference numerals indicate like parts throughout the drawings.

The press comprises a box-shaped frame having a removable front access plate 15, a removable rear access plate 16 and side cheeks 17 and 18, which latter are stiff and form part of the permanent structure. Supported by the frame towards the front thereof is an upstanding pillar 19 to which is fixed the lower buck 20 which may be heated by steam supplied through a pipe 21. Secured between the side cheeks 17 and 18, and assisting to stiffen the press frame is a strut 22 which may be a tube, or a solid bar with bushes. This strut 22 constitutes a spindle on

40 which is pivoted a composite arm for the movable head 23. This composite arm comprises side plates 24 and 25 which at their lower ends are pivoted upon the spindle 22 and at their upper ends are joined by a head 26 which receives the buck 23. The latter may be heated by steam supplied

through a pipe 37. The steam may be discharged from the buck 20 and the head 23 through pipes which are not shown but are similar to the pipes 21 and 37. These discharge pipes are preferably connected to a steam trap.

Situated between the side cheeks 17 and 18 is a two-diameter cylinder 27 formed with brackets 28 and 29 whereby it is secured to the cheeks. It is of stiff construction and serves to brace the press frame. One end of the cylinder 27 is closed 10 by a cover 30 and the other end of the cylinder is open but is fitted with a protecting hood 31 of conical formation.

Received to reciprocate in the cylinder 27 is a piston head 32 having a trunk 33 reaching from one face thereof. The piston head 32 closely fits in the larger part of the cylinder 27 and is provided with cup leathers 34 or piston rings. The trunk 33 closely fits in the smaller part of the cylinder 27 and is provided with a cup leather 35 or a piston ring. It will be seen clearly from Figure 5 that the face of the piston head 32 towards the left presents its full circular area to the cylinder space but the face towards the right presents only an annulus to the cylinder space. Thus the opposed exposed faces of the piston head are of different areas.

Pivoted in the piston head 32 and reaching through the trunk 33 and the hood 31 is a connecting rod 36 which is joined to the side plates 24 and 25 of the pressing head arm by a toggle linkage. This toggle linkage comprises an upper and a lower link pivoted together whereof the former is also pivoted to the connecting rod 36 and the arm for the movable head 23, and the lower link is anchored between the cheeks 17 and 18 of the frame. Referring more particularly to Figures 2 and 3, it will be seen that the upper link comprises arms 38 and 39 formed integral with barrels 40 and 41. The barrel 40 is received between bushes 42 and 43 carried respectively by the side plates 24 and 25 of the pressing head arm, and reaching right through the barrel 40 and the bushes 42 and 43 is a tube 44 or a solid bar with bushes constituting a spindle whereby the upper link is pivotally connected to the pressing head arm. The brackets 28 and 29 reach towards the cylinder 27 to embrace the end of the connecting rod 36 (see particularly Figure 5) and reaching through these parts is 50 a tube 45 or a solid bar with bushes which affords pivotal connection between the upper link and the connecting rod. The barrel 41 of the upper link is received between brackets 46 and 47 in the lower link and a tube 48 or a solid bar with bushes reaching through these parts serves as a pivotal connection between the upper and lower links. The lower link also comprises a barrel 49 formed integral with the brackets 46 and 47. This barrel is received between bushes 50 and 51 carried by the cheeks 17 and 18 of the frame of the press, and a strut 52, which may be a tube or a solid bar with bushes, reaches through these parts in such manner as to be secured to the side cheeks 17 and 18 and serve both to pivot the lower link in the frame of the press and to brace the latter. It will be understood that as the piston head 32 reciprocates in the cylinder 27 the toggle linkage just described will move between the settings shown in Figures 1 and 2 and correspondingly move the buck 23.

It is preferred to employ compressed air to bring the buck 23 into operative position and

apply the ironing pressure and to bring the head 23 out of operative position. The main supply pipe for this compressed air is shown at 53. This pipe 53 reaches to the front of the machine 5 where it delivers the compressed air to the interior of the casing 54 of an operator's control valve. Also communicating with the interior of the valve casing 54 is a pipe 55 which is connected to a port 56 in the cover 30 for the larger end of the cylinder 27. This pipe 55 serves both to supply compressed air to the larger end of the cylinder 27 and to permit its exhaust therefrom. Situated in the pipe 53 is a junction box 107 (Figures 4, 5 and 6), the interior of which communicates with a port 57 in the wall of the cylinder 27 at the junction of the larger and smaller portions of the latter. This port 57 is therefore exposed to the annular space formed by the piston head 32 and the trunk 33 and it serves both to supply compressed air to this annular space and to exhaust it therefrom. The annular space, however, is always open to the interior of the pipe 53. By a suitable manipulation of his control valve (hereinafter described) the operator can admit compressed air through the port 56 in order to force the piston head 32 to the right, as seen in Figure 5, and bring the head 23 into the position shown in Figure 2, applying the necessary ironing pressure. During this movement of the parts the air in the annular space formed by the piston head 32 and the trunk 33 will be expelled through the port 57 back into the pipe 53. The resistance offered by this air to its expulsion through the port 57 will cushion the movement of the piston head and thus minimise jar and shock. When the ironing operation is completed, the operator will manipulate his control valve in such a way as to permit the air from the larger end of the cylinder 27 to be exhausted through the port 56 back into the pipe 55 and the valve casing 54. As the annular space formed by the piston head 32 and the trunk 33 is open to the pipe 53 compressed air will now pass from the latter through the port 57 into this annular space and force the piston to the left, as seen in Figure 5, thus moving the head 23 into the position shown in Figure 1 and maintaining it there until a further manipulation of the operator's control valve occurs.

The cushioning effect just described can be varied by regulating the rate at which the air is exhausted from the aforesaid annular space through the port 57. For this purpose the box 107 is provided with a screwthreaded needle valve 58 which, as seen in Figure 6, reaches across the bore in the box 107 to a port 59. The rim of this port forms a seat for a valve 60 which controls the port 57. A spring 61 urges the valve 60 towards its seat. The valve has a passage 62 through it which is not closed by the valve engaging its seat and the point of the needle valve 58 reaches into this passage 62. By adjusting the setting of the needle valve 58 it will be seen that the size of the aperture left between the point of the needle valve and the walls of the passage 62 can be varied so as to regulate the rate of exhaust through the port 57 and correspondingly regulate the aforesaid cushioning effect. It is not desired that the entry of compressed air into the cylinder 27 through the port 57 should be strangled and it is for this reason that the movable valve 60 is provided. As will be seen from Figure 7 it has splines 63 by which it is guided in its movement

inside the box 107. These splines reach below the end of the body of the valve 60 and thus when the valve has been moved downwardly as seen in Figure 6 into such a position that the ends of the splines engage the cheek 17 of the press frame on which the box 107 is mounted, passages will be afforded between the ports 57 and 59 around the outside of the valve 60, in addition to the passage 62 through the interior of the valve 60. Thus when the valve is on its seat it affords a smaller orifice for the passage of the air than when it is off its seat. Air proceeding from the aforesaid annular space in the cylinder 27, through the port 57, will operate on the valve 60 in the direction to urge it towards its seat, but air passing from the pipe 53 through the port 59 towards the annular space will operate on the valve 60 in the opposite direction and will overcome the pressure of the spring 61 and force the valve from its seat, thus enabling compressed air, for lifting the head 23, to reach the annular space readily.

Figures 8 to 11 show the construction of the operator's control valve which, however, does not form part of the present invention and is only described herein in order that the operation of the press may be understood. The casing 54, already mentioned, of this valve is mounted on the downwardly-turned rim 64 of a table 65 at the front of the press under the buck 20. The casing 54 is bored from top to bottom and the lower end is closed by a screwed plug 66. A boss 67 on the casing receives the end of the aforesaid pipe 53 and another boss 68 receives the end of the aforesaid pipe 55. Opposite to the end of the pipe 55 there is a constriction in the bore in the casing 54 and this constriction is fitted with a liner 69. The lower end of this liner is shaped to serve as a seat to be engaged by a ball valve 70 which is pressed upwardly by a spring 71 housed in a recess in the plug 66. When the ball 70 is on its seat it prevents the passage of compressed air from the pipe 53. The upper end of the liner 69 has an out-turned flange 72 which abuts on a shoulder in the bore in the casing 54. Above the liner 69 is a valve stem 73 and a valve 74. The valve 74 has an extension 75 reaching down to the ball valve 70 and at the neck of this extension there is a conical surface 76 which is intended to seat against the end of the bore of the liner 69. When in this position it closes communication between the pipe 55 and a lateral exhaust port 77 in the casing 54. This port leads into an exhaust silencer 78 whereof the walls are suitably perforated. The opposed faces of the stem 73 and valve 74 are recessed to house a spring 79 by which the stem 73 may press the valve 74 against the upper end of the liner 69. The upward pressure of the spring 71 is reinforced by the pressure of the air in the pipe 53. The stem 73 is laterally bored to receive a relatively small cross pin 80 secured in the casing 54. This pin limits the longitudinal movement of the stem 73. The upper end of the stem 73 has pivoted to it by a pin 87 an arm 81, the clearance indicated at 82 in Figure 8 enabling the arm 81 to tilt through a substantial angle with respect to the stem 73. This arm is semi-circularly cut away at 83 and 84 to clear pins 85 and 86 secured in cheeks 87 and 88 upstanding from the valve casing 54. These pins 85 and 86 serve respectively as pivots for two finger levers 89 and 90. The finger lever 89 is bifurcated to form two legs 91 and 92 which receive the pin 85, and the finger lever 90 is similarly bifurcated to form two

legs 93 and 94 which receive the pin 86. Cross pins 95 and 96 carried respectively by the finger levers 89 and 90 are adapted to engage the upper surface of the arm 81. If both finger levers 89 and 90 are depressed the stem 73 will in turn be depressed and thus cause the valve 74 to move the ball valve 70 off its seat. A downwardly-directed channel-shaped guard plate 98 is fitted over the finger levers 89 and 90 to prevent accidental depression of these finger levers or depression by one hand only.

The stem 73 has a circumferential recess 99 lying opposite to a short catch rod 100. This rod 100 is mainly cylindrical and is housed in a cylindrical hole in the casing 54. The longitudinal axis of this hole is so placed in regard to the stem 73 that the rod 100 has to be cut away to accommodate the stem 73. When, however, the stem 73 is sufficiently depressed to bring its recess 99 opposite to the rod 100 the latter can rotate into the recess 99 and thus prevent longitudinal movement up or down of the stem 73. In this depressed position the stem 73 will be causing the extension 75 to hold the ball valve 70 off its seat. The rod 100 reaches at both ends to the outside of the casing 54. At one end it carries a pin 101 to which is attached one end of a spring 102, the other end of which is anchored to a pin 103 reaching out from the lower end of the valve casing. This spring tends to rotate the rod 100 in the counterclockwise direction, as seen in Figure 8, so as to turn the rod 100 into engagement with the recess 99 when the stem 73 has been suitably depressed by the operator. The other end of the rod 100 has attached to it a finger lever 104 with a tail piece 105 which latter is adapted to come to rest against a pin 106 reaching out from the valve casing. By means of the finger lever 104 the operator can rotate the rod 100 against the pull of the spring 102 so as to bring the rod 100 into the position in which it will release the stem 73 and permit it to return to the upper limit of its longitudinal travel, but the pin 106 will prevent the operator from depressing the lever 104 sufficiently far to bring the upper part of the rod 100, as seen in Figure 8, into engagement with the recess 99.

The operation of the press may be described as follows: Since the port 57 is always open to the pipe 53 the compressed air will tend to maintain the movable head 23 in the position shown in Figure 1. When the operator has spread an article on the buck 20 ready for ironing, he places one finger from each hand inside the guard 98 and depresses both of the finger levers 89 and 90. This causes the extension 75 to open the ball valve 70 and permit compressed air to enter the pipe 55 and reach the larger end of the cylinder 27, thus moving the head 23 into the position shown in Figure 2 and applying the ironing pressure. As the stem 73 is thus depressed by the operator the rod 100 will turn automatically into the recess 99 and hold the stem 73 depressed and thus keep the ball valve 70 open. In this position of the parts, the compressed air operating against the left-hand side of the piston head 32, as seen in Figure 5, overcomes the pressure of the compressed air acting in the annular space formed by the piston head 32 and the trunk 33. When the ironing is finished, the operator depresses the lever 104 whereupon the parts 73 and 74 move upwardly, shutting off the pipe 53 from the pipe 55 and opening the latter to the exhaust port 77. This

will exhaust the compressed air from the larger end of the cylinder 27 and permit the compressed air acting in the aforesaid annular space to return the movable head 23 to the position shown in Figure 1.

It is to be understood that the invention is not restricted to the precise constructional details set forth.

We claim:

1. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed faces of the piston head in the larger part of the cylinder are of different areas, means for admitting fluid pressure at will to and shutting it at will off from that end of the larger part of the cylinder to which the piston face of larger area is directed and for admitting fluid pressure continuously to the other end of the larger part of the cylinder, and means connecting the piston head to the movable head in such manner that fluid pressure on the piston face of larger area operates to bring the movable head into operative position and apply the ironing pressure, and that fluid pressure on the piston face of smaller area operates to bring the movable head out of operative position.

2. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed faces of the piston head in the larger part of the cylinder are of different areas, means for admitting fluid pressure at will to and shutting it at will off from that end of the larger part of the cylinder to which the piston face of larger area is directed, means for subjecting the piston face of smaller area continuously to fluid pressure and for permitting the exhaust of fluid from that end of the larger part of the cylinder to which the piston face of smaller area is directed, means for regulating the rate of said exhaust, and means connecting the piston head to the movable head in such manner that fluid pressure on the piston face of larger area operates to bring the movable head into operative position and apply the ironing pressure, and that fluid pressure on the piston face of smaller area operates to bring the movable head out of operative position.

3. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed faces of the piston head in the larger part of the cylinder are of different areas, means for admitting fluid pressure at will to and shutting it at will off from that end of the larger part of the cylinder to which the piston face of larger area is directed, means for subjecting the piston face of smaller area continuously to fluid pressure and for permitting the exhaust of fluid from that end of the larger part of the cylinder to which the piston face of smaller area is directed, a needle valve for regulating the rate of said exhaust, and means connecting the piston head to

the movable head in such manner that fluid pressure on the piston face of larger area operates to bring the movable head into operative position and apply the ironing pressure, and that fluid pressure on the piston face of smaller area operates to bring the movable head out of operative position.

4. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed faces of the piston head in the larger part of the cylinder are of different areas, means for admitting fluid pressure at will to and shutting it at will off from that end of the larger part of the cylinder to which the piston face of larger area is directed, means for subjecting the piston face of smaller area continuously to fluid pressure and for permitting the exhaust of fluid from that end of the larger part of the cylinder to which the piston face of smaller area is directed, a needle valve for regulating the rate of said exhaust, means for adjusting said needle valve, and means connecting the piston head to the movable head in such manner that fluid pressure on the piston face of larger area operates to bring the movable head into operative position and apply the ironing pressure, and that fluid pressure on the piston face of smaller area operates to bring the movable head out of operative position.

5. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed faces of the piston head in the larger part of the cylinder are of different areas, means for admitting fluid pressure at will to and shutting it at will off from that end of the larger part of the cylinder to which the piston face of larger area is directed, a single conduit serving for supplying and exhausting pressure fluid to and from the other end of the larger part of the cylinder, means connecting the piston head to the movable head in such manner that fluid pressure on the piston face of larger area operates to bring the movable head into operative position and apply the ironing pressure, and that fluid pressure on the piston face of smaller area operates to bring the movable head out of operative position, a valve for controlling said conduit, a seat in the conduit for said valve, and a spring urging said valve towards its seat, which parts are so constructed and arranged that when the valve is on its seat it affords a smaller orifice for the passage of the fluid than when it is off its seat, and that the fluid in proceeding from the cylinder along said conduit operates on the valve in the direction to urge it towards its seat, and in proceeding to the cylinder along said conduit operates on the valve in the opposite direction to overcome the pressure of said spring and force the valve from its seat.

6. An ironing press comprising in combination a movable pressing head, a co-operating buck, a piston head, a trunk reaching from one face thereof, a two-diameter cylinder, the larger and smaller parts of which closely fit the piston head and piston trunk respectively and the diameter of which trunk is such that the opposed exposed

faces of the piston head in the larger part of the cylinder are of different areas, means for admitting fluid pressure at will to and shutting it at will off from that end of the larger part of the cylinder to which the piston face of larger area is directed, a single conduit serving for supplying and exhausting pressure fluid to and from the other end of the larger part of the cylinder, a needle valve for regulating the rate of said exhaust, means connecting the piston head to the movable head in such manner that fluid pressure on the piston face of larger area operates to bring the movable head into operative position and apply the ironing pressure, and that fluid pressure on the piston face of smaller area operates to bring the movable head out of operative position, an automatic valve for controlling said conduit, a seat in the conduit for said automatic valve, which automatic valve has a passage

through its body which is not closed by the automatic valve engaging its seat but which is controlled by the said needle valve, and a spring urging said automatic valve towards its seat, which parts are so constructed and arranged that when the automatic valve is on its seat it affords a smaller orifice for the passage of the fluid than when it is off its seat, and that the fluid in proceeding from the cylinder along said conduit operates on the automatic valve in the direction to urge it towards its seat, and in proceeding to the cylinder along said conduit operates on the automatic valve in the opposite direction to overcome the pressure of said spring and force the automatic valve from its seat.
